UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,601, dated August 28, 1894.

Application filed August 3, 1894. Serial No. 519,373. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls forming a series of ornaments with 10 groups of flowers and leaves of roses extending upwardly from said ornaments and festoons of flowers and leaves connecting the scrolls and forming with the scrolls ornamental panels as represented in the accompanying drawing. The border or upper portion of 15 the design is formed of continuous running scrolls with sprays of flowers and leaves of roses springing from said scrolls and festoons of flowers and leaves of roses connected to said scrolls as represented in the drawing. A 20 narrow striped band forms the top and bottom of the border.

What I claim is—

1. The design for wall paper herein shown and described. 25
2. In the design for wall paper, the border herein shown and described.

Witness my hand this 31st day of July, 1894.

CHARLES BOOZE.
